UNITED STATES PATENT OFFICE.

CHARLES M. DAY, OF HOPEDALE, MASSACHUSETTS, ASSIGNOR TO DRAPER COMPANY, OF HOPEDALE, MASSACHUSETTS, A CORPORATION OF MAINE.

MOLDING APPARATUS.

SPECIFICATION forming part of Letters Patent No. 697,134, dated April 8, 1902.

Application filed October 17, 1901. Serial No. 78,928. (No model.)

To all whom it may concern:

Be it known that I, CHARLES M. DAY, a citizen of the United States, and a resident of Hopedale, county of Worcester, State of Massachusetts, have invented an Improvement 5 in Molding Apparatus, of which the following description, in connection with the accompanying drawings, is a specification, like letters and numerals on the drawings representing like parts.

This invention relates to apparatus for facilitating and improving the construction of molds for metal-foundering, whereby very accurate and fine molds can be rapidly constructed without the use of highly-skilled and expensive labor, the general type of apparatus to which my invention belongs containing as essential features a stripper-plate and a relatively movable pattern.

20 My present invention has for its object the production of improved molding apparatus of the general type referred to with novel means for "drawing" the pattern, and more especially when the pattern must have imparted thereto a compound movement to draw it 25 from the mold.

The various novel features of my invention will be hereinafter described in detail in the specification, and particularly pointed out in 30 the following claims.

Figure 1 is a front elevation, partly broken out and in section, of a molding apparatus embodying one form of my invention, the patterns being shown in operative position relative to the stripper-plate. Fig. 2 is a top or plan view thereof, the stripper-plate and a portion of the frame being broken out and one of the patterns being omitted; and Fig. 3 is a vertical longitudinal section of a pattern 35 and the means for controlling the longitudinal movement thereof, the pattern-carrier being shown in elevation.

In the present embodiment of my invention I have shown an apparatus for molding articles having an external spiral thread—such, for instance, as a worm—it being manifest that in order to "draw" the pattern of such an article from the mold the pattern must be given a compound movement, the resultant 40 of a rotative movement and a longitudinal movement, the latter corresponding with the

pitch of the spiral thread of the pattern. I have also shown the apparatus arranged for the formation of a plurality of molds simultaneously; but manifestly a single pattern 55 could be used to form a single mold, and such construction clearly is within the spirit and scope of my invention.

Referring to Figs. 1 and 2, a base-plate A, of suitable shape and size to sustain the parts 60 of the apparatus, is mounted on legs A' in order to bring the upper portion of the apparatus into convenient position, the base-plate having erected upon it four standards A², 65 which support a horizontal guide-plate G, 65 which is provided with a series of upright tubular bearings g, one for each pattern-carrier, to be described, and in the present embodiment of my invention I have provided for eight pattern-carriers arranged, as shown in 70 Fig. 2, in two rows of four each. The guide-plate has upturned corner-posts g^x, to the upper ends of which is secured a stripper-plate S, the stripper-plate being used in the construction of the mold to form the parting- 75 face thereof in a manner well known in the art of machine-molding. The stripper-plate is provided at its opposite ends with horizontally-extended ears s s', one of them, as the ear s, having a hole 2 therein, while the opposite ear s' has secured to it an upright pin or short stud 3, the object of the two ears being to accurately position the drag-flask during the construction of the drag, said flask having ears at its ends, one of which has a hole 80 85 to receive the pin 3 and the other being provided with a pin or stud to enter the hole 2, it being understood that when the apparatus is to be used the pattern or patterns will be moved into operative position relative to the 90 stripper-plate, as shown in Figs. 1 and 2, and the drag-flask will then be placed upon the stripper-plate and filled with molding-sand and rammed, all in usual manner, before the pattern or patterns will be withdrawn. The 95 stripper-plate is provided with circular openings s^x, (see Fig. 1,) one for each pattern, and located above and concentric with one of the vertical bearings g, hereinbefore referred to.

I have herein shown the apparatus as provided with a plurality of like patterns for making molds for worms, each pattern com-

prising a barrel p , having an external spiral thread p^x and a slightly-tapered extension p' at the upper end of the barrel, said extension being shown as provided with a core-print p^2 to form a seat in the bottom of the mold for the reception of a core, inasmuch as the casting to be produced has a longitudinal opening therethrough for the reception of a shaft to which the completed worm is to be secured.

The pattern as a whole will be hereinafter designated as P , and inasmuch as the patterns are precisely alike the description of one will suffice for all, and, referring to Fig. 2, it will be noted that the end of the spiral thread nearest the extension p' turns into and merges with the cylindrical barrel, as at p^3 , the other end of the thread being continued to the point p^4 , (see Fig. 1,) and shown by breaking out the stripper-plate, and it will also be noticed by reference to this figure that the lower end of the thread enters the pattern-opening s^x in the stripper-plate when the pattern is in its operative position.

The barrel of each pattern P is made hollow, as shown in Fig. 3, and the extension p' has a socket p^5 therein to receive and form a seat for the upper end of the pattern-carrier C , herein shown as a long spindle or shaft extended through the bearing g of the guide-plate G and below the said plate into a second bearing a^x on the base-plate A , the latter having an aperture, as a' , for each of the bosses, through which the corresponding pattern-carrier may be moved longitudinally in the operation of the apparatus. A suitable pin 5, adapted to be driven into the upper end of the pattern-carrier through a hole in the extension p' , serves to firmly secure the pattern to the carrier. Each carrier has rigidly secured thereto and below the guide-plate the hub b of a gear or sprocket-wheel b^x , a set-screw 6 holding the hub securely in place, and the upper face of the sprocket-wheel or gear is provided with an elongated sleeve-like extension or shaft b' , which surrounds with an easy fit an elongated nut N , in the present embodiment of my invention shown as fixedly mounted upon the under side of the guide-plate G by means of suitable screws 7, extended into said plate through an annular flange n^x at the upper end of the nut, which latter is spirally threaded, the pitch and length of the spiral corresponding to the spiral thread of the pattern, and I have herein shown what I have termed a "master-thread" M as secured to or forming a part of such carrier and in operative engagement with the nut, so that rotative movement of the carrier will by or through the co-operation of the master-thread and nut effect a longitudinal movement of the carrier in exact correspondence with the pitch of the thread of the pattern, so that the pattern will be given a compound rotative and longitudinal movement to unscrew it, as it were, from the mold when the latter is completed.

The bearings g enter the hollow barrels p of the patterns P as the latter are moved downward in the operation of drawing, and they 70 act to steady each pattern after a portion of it has been drawn from the sand, and it will be manifest that the longitudinal movement of the pattern need only be sufficient to entirely withdraw the spiral portion thereof from 75 the spiral portion in the mold.

The pattern-openings s^x in the stripper-plate are counterbored, as at s^5 , Fig. 1, to receive a filling-ring made for convenience in three parts $f f' f^2$, the segments $f f'$ when in 80 position leaving an opening 10 of a shape corresponding to the leading end of the pattern-spiral, and through which the spiral travels when the pattern is moved into and out of operative position. The third segment f^2 has 85 an inclined top f^3 , corresponding to the slope of the pattern-spiral, and presents a substantially wedge-shaped stopping-off piece or filler, which in Fig. 1 is indicated at f^x , the object of this filler being to prevent the formation of a thin unsupported portion of sand 90 in the mold adjacent the parting-face and running to a feather-edge.

By examining any one of the three left-hand patterns in Fig. 1 it will be seen that the filler 95 f^x forms practically a continuation of a portion of the pattern-spiral adjacent the top of the stripper-plate, and it will be manifest that if no such device were used the sand would form a thin wedge-shaped tongue running to a 100 feather-edge, and it would be impossible to prevent this tongue from breaking off either during the drawing of the pattern or thereafter, and to overcome this objectionable feature the 105 filler is used to stop off the sand at a point where it will be sufficiently thick to support itself properly after the pattern has been drawn.

Usually the cope, which may be made on an ordinary "flat-back," will have a projection to fit into the recess in the mold formed by the use of the stopping piece or filler, thus completing the mold, the term "flat-back" meaning, technically speaking, a flat plate with such portions of a pattern rigidly secured 115 thereto as can be readily drawn from the mold.

I have herein provided actuating means for imparting rotative movement to the pattern-carriers, the actuating means being so constructed and arranged that the longitudinal movement of the pattern-carriers is accompanied by a similar movement of the actuating means.

The base-plate A has erected upon it at its left-hand end an upright stand D , the base 125 thereof having lateral feet d , through which are extended the shanks of suitable bolts d^x , said shanks passing through longitudinal slots a^3 (see Fig. 1) in the base-plate A and being held in adjusted position by means of set-nuts a^4 to securely clamp the stand D in adjusted position, a ready adjustment being effected by means of an adjusting-screw d' , mounted in an ear a^5 on the base-plate A and

bearing against the base of the stand D, so that by slackening up the nuts a^4 and turning the adjusting-screw d^l in one direction or the other the position of the stand may be changed relative to the main framework of the apparatus on which the pattern apparatus is mounted.

An upright shaft D^x is rotatably mounted in a bearing d^2 on the top of the stand, and at its lower end the said shaft passes through a hole in the base of the stand and in the base-plate A, said shaft having secured to it a sprocket-wheel or gear d^3 , provided with an upturned sleeve-like shield d^4 , which latter receives with a sliding fit a downturned externally-cylindrical nut d^5 , secured at its upper end to the top of the stand D, this nut being interiorly threaded to coöperate with a master-thread d^6 , secured to the shaft D^x . I have not deemed it necessary to illustrate this structure in detail, as the sprocket-wheel, shield, nut, and coöperating master-thread for the shaft D^x of the actuator are all like similar parts hereinbefore described in detail as effecting the longitudinal movement of a carrier, the sprocket-wheel d^3 of the actuator being connected by an endless sprocket-chain 50 with the sprocket-wheels b^x of the pattern-carriers, as clearly shown in Fig. 2.

The shaft D^x is provided with an operating-handle D^3 , and manifestly by rotating the shaft the sprocket-chain will impart simultaneous rotation to the pattern-carriers, and as the latter are moved longitudinally by means hereinbefore described the actuator-shaft D^x will be moved longitudinally in unison therewith, so that the chain is moved up or down, according to the direction of longitudinal movement of the carriers, without any twisting or kinking, and inasmuch as every carrier is like its fellows they will be moved in absolute unison and all of the patterns will be accurately and simultaneously drawn from the mold, or if the actuator is rotated in the opposite direction, supposing the patterns to be in their inoperative position, then the said patterns will be simultaneously moved into operation position shown in the drawings.

The function of the sleeve-like shield b' is to protect the master-thread from injury by the entrance of sand or dirt, and a like function is fulfilled by the shield d^4 of the actuator, the upper ends of the shields still embracing the nuts when the patterns are in the position which they will assume when fully drawn from the mold.

In order to insure the correct engagement of the sprocket-chain with the sprocket-wheels or gears of the carriers and to guide the said chain, I have herein shown idler-drums I I', rotatably mounted on suitable upright studs k k' , secured to the base-plate A, the chain being maintained properly taut by adjustment of the stand D, hereinbefore described.

While I have shown a multiple-pattern apparatus herein adapted for the formation of

a number of molds at one time in the drag, it will be manifest that the apparatus is equally well adapted for single-pattern work, if desired, as the operation is the same whether one pattern or a plurality of patterns be used.

By using different segment-pieces in the pattern-apertures s^x of the stripper-plate 75 the apparatus can be used for patterns of different diameters, the segmental ring formed by the members $f f' f''$ acting to support the sand at the parting-face when the pattern is withdrawn, the inner edge of the opening 80 formed by such segmental ring being closely adjacent the external circumference of the pattern.

The bearings f not only serve to laterally support the pattern-carriers and to provide 85 long bearings therefor, but they also, in connection with the guide-plate G, aid in protecting the master-threads from the entrance of sand or dirt.

Various changes or modifications may be 90 made in the apparatus herein shown and described without departing from the spirit and scope of my invention.

Having fully described my invention, what I claim as new, and desire to secure by Letters 95 Patent, is—

1. In a molding apparatus, a fixed stripper-plate, a coöperating spirally-threaded pattern, a rotatable and longitudinally-movable carrier therefor having a master-thread of 100 the same pitch, a fixed nut coöperating with the master-thread, fixed bearings located above and below the master-thread and nut, and independent of the stripper-plate to support the carrier laterally and permit longitudinal movement thereof at right angles to the stripper-plate, and means to rotate the carrier, said means including a gear fast on the carrier, coöperation of the master-thread and nut effecting longitudinal movement of 110 the carrier simultaneously with its rotative movement, to thereby draw the pattern.

2. In a molding apparatus, a fixed stripper-plate, a coöperating spirally-threaded hollow pattern, a rotatable and longitudinally-movable carrier therefor, a fixed tubular bearing 115 for the carrier, to enter and steady the pattern when drawn, a master-thread and a coöperating nut, one being fixedly mounted independent of the stripper-plate, and the other attached to the carrier, to effect longitudinal movement of the latter when rotated, and means to rotate the carrier.

3. In a molding apparatus, a fixed stripper-plate, a plurality of like coöperating spirally-threaded hollow patterns, a carrier for each pattern, fixed bearings through which the carriers move and which enter and guide the patterns when drawn, and means to rotate in unison the said carriers and simultaneously 130 move them and their attached patterns longitudinally in correspondence with the pitch of the pattern-threads, to thereby draw the patterns.

4. In a molding apparatus, a fixed stripper-plate, having a plurality of openings therein, a plurality of like spirally-threaded patterns freely movable through said openings, a rotatable and longitudinally-movable carrier for and to which each pattern is secured, a fixed guide-plate having on its upper face tubular bearings through which the carriers freely move, a master-thread on each carrier of the pitch of the pattern-thread, a fixed nut depending from and secured to the guide-plate to coöperate with each master-thread, and means to rotate in unison the carriers, and to move longitudinally with them, longitudinal movement of said carriers being simultaneously effected by the master-threads and nuts, to draw the patterns.
5. In a molding apparatus, a fixed stripper-plate, a plurality of like, spirally-threaded patterns to coöperate therewith, a rotatable and longitudinally-movable carrier for each pattern, two fixed bearings for each carrier, one near the pattern, and the other at or near the lower end of the carrier, a master-thread and a coöperating nut for each carrier, one being attached to the carrier and the other fixed, to effect longitudinal movement of the several carriers when rotated, said master-thread and nut being located between the bearings for each carrier, and means to rotate the carriers in unison, said means including a gear fast on each carrier, and a common actuating device in engagement with the several gears.
- 35 6. In a molding apparatus, a fixed stripper-plate, a coöperating spirally-threaded pattern,

a rotatable carrier therefor movable at right angles to the stripper-plate and having an attached sprocket-wheel, a master-thread on the carrier, having the pitch of the pattern-thread, a coöperating fixed nut, a rotatable actuator having an attached sprocket-wheel, a sprocket-chain connecting said sprocket-wheels, and means to move the actuator longitudinally in unison with the carrier, whereby rotation of the actuator will operate the carrier to draw the pattern.

7. In a molding apparatus, a fixed stripper-plate, a plurality of rotatable carriers movable at right angles to the stripper-plate and each having an attached sprocket-wheel, a spirally-threaded pattern mounted on each carrier, means to move said carriers longitudinally in correspondence with the pitch of the pattern-threads when rotated, a rotatable and longitudinally-movable actuator having an attached sprocket-wheel, and an endless sprocket-chain connecting said sprocket-wheel with the sprocket-wheels of the several carriers, whereby rotation of the actuator imparts rotation to the carriers, to draw the patterns, the longitudinal movement of the actuator corresponding to the longitudinal movement of the carriers.

In testimony whereof I have signed my name to this specification in the presence of two subscribing witnesses.

CHARLES M. DAY.
